UNITED STATES PATENT OFFICE.

JOSEPH HEATON SOUTHERN, OF MIDDLESBROUGH, ENGLAND.

METAL REINFORCEMENT FOR CONCRETE.

Application filed March 21, 1924. Serial No. 700,805.

To all whom it may concern:

Be it known that I, JOSEPH HEATON SOUTHERN, of Messrs. Richard Hill & Company, Limited, Newport Rolling Mills, Middlesbrough, in the county of York, England, a subject of the King of Great Britain and Ireland, have invented certain new and useful Improvements in Metal Reinforcements for Concrete, of which the following is a specification.

This invention relates to the methods for reenforcing concrete structures by means of welded metal fabric, expanded metal, woven metal fabric, or metal bars or wires, particularly adapted for use in the construction of roads, rafts, reservoirs, retaining walls, floors, silos, ships, hoppers, coast defence works, columns, beams, culverts, pipes, piles, and the like structures.

The object of this invention is to provide a simple and efficient reenforcement which may be manufactured in separate component parts adapted to be easily and conveniently transported to the site of the work and quickly assembled thereon in situ to form a "mat" or the like by unskilled or partly skilled labour.

Metal reenforcement for concrete made in accordance with this invention comprises upper and lower reenforcing members and an intermediate fabricated member of zig-zag formation composed of welded metal, expanded metal, woven metal or metal bars or wires secured together, the upper, lower and intermediate members being assembled in situ.

The accompanying drawings illustrate one form of metal reenforcement made of metal rods or wires in the form of welded fabric in accordance with this invention, and adapted for use in concrete roads or the like, and of the several figures shewn therein:—

Fig. 1 is a plan view of one form of frame made of wire or bars secured together suitable for use as an upper and/or a lower member of the reenforcing "mat."

Fig. 2 is a side elevation thereof.

Fig. 3 is a plan view of the longitudinal intermediate zigzag reenforcing member, and

Fig. 4 is a side elevation thereof.

Fig. 5 is a side elevation of one form of transverse zigzag reenforcing member, and

Fig. 6 is an end elevation thereof.

Fig. 7 is a plan view of the reenforcing

"mat" with all the components assembled in position.

Fig. 8 is a side elevation thereof, and

Fig. 9 is a corresponding end elevation.

Fig. 10 is a side elevation shewing a modified arrangement of the members.

Fig. 11 is a side elevation shewing a modified form of longitudinal intermediate member.

In Figs. 1 to 9, the upper and lower frames

of the reenforcing "mat" are each composed of a number of parallel longitudinal bars or wires *a a'* spaced apart at regular intervals by transverse wires or bars *b b'* welded or otherwise rigidly secured thereto at *c*. The longitudinal intermediate member is composed of a number of parallel longitudinal bars or wires *d* bent to the zigzag form shown in Fig. 4 and spaced apart at suitable regular intervals, but preferably correspond-

ing to the intervals between the longitudinal bars *a a'* in the upper and lower members, by transverse positioning and supporting bars or wires *e e'* disposed near the ridges and valleys of the zigzag longitudinal bars *d* and welded or otherwise rigidly secured thereto. The transverse zigzag members *f*, shewn in Figs. 5 and 6, are formed of bars or wires having loops *g g'* at the upper and lower apices. The transverse locking members are formed of straight bars or wires *h h'*.

In operation, assuming that the reenforcement is to be used in a concrete road, the lower longitudinal member or frame is laid first. The longitudinal intermediate member is then placed in position with the transverse bars *e'* resting across and on top of the longitudinal bar *a'* of the lower member so that the valleys of the intermediate zigzag member project below said longitudinal bars *a'*. The transverse locking members *h'* are placed in the valleys under the lower member so that said lower member is locked between the locking bars *h'* and the transverse bars *e'*. The transverse zigzag members *f*, when used, are placed in some or all of the valleys and/or under some or all of the ridges of the longitudinal intermediate members before the locking members *h'* are placed in position, said locking member *h'* being then placed through the loops *g'*. The upper member is then placed in position with the longitudinal bars *a* resting on the transverse supporting bars *e* of the intermediate member so that the ridges of the

intermediate member project above the upper member. The transverse locking member h is then placed in the ridge above the upper member, and, if used, through the 5 loops g of the transverse zigzag member f . The longitudinal and transverse intermediate zigzag members are for the purpose of taking up the longitudinal and transverse shear or diagonal tension in the concrete. 10 The transverse locking members h h' also provide a transverse reenforcement.

In Figs. 7, 8 and 9, the ridges and valleys of the longitudinal bars d of the zigzag intermediate member are shown all on one 15 side of the longitudinal bars a a' of the upper and lower members for convenience of illustration. In practice it will probably be found preferable to alternate consecutive ridges and valleys on either side of the bars 20 a a' so as to prevent sideward movement of the intermediate member. This arrangement is shown in Fig. 10 wherein the ridges 1 and 5, and the valley 4, are shown on the near side of the bars a a' , whilst the 25 alternating ridge 3, and valley 2, are shown on the far side of said bars a a' . It will be understood that all the ridges and valleys in the same transverse plane of the intermediate member will be on the same side 30 of the bars a a' , the transverse tie bars e e' positioning them. Transverse sliding movement of the transverse zigzag members f along the locking bars h h' is prevented by placing the loops g g' between the ridges 35 or valleys of the intermediate member and the bars a a' .

In the modified construction shewn in Fig. 11 the longitudinal intermediate member is composed of elements m on to which positioning and supporting bars n n' are welded or otherwise secured. The locking bars h' are placed in the valleys of the intermediate member as before to lock said intermediate members to the lower member. The 45 hooked upper ends of the elements m are bent over the transverse positioning bars b of the upper member, after said upper member has been placed in position, on the transverse bars n of the intermediate member. The transverse bars b will then also 50 serve as locking bars.

For the purpose of further security or rigidity additional transverse positioning or supporting bars e^2 e^3 may be secured to 55 the longitudinal zigzag bars d as shewn dotted in Fig. 8.

The upper, lower and longitudinal intermediate frames can be made on a standard welding, weaving or expanded metal machine, or by hand, to any width or length required.

Reinforcing "mats" made in accordance with this invention may be superposed to obtain greater depth if required, for example, a further longitudinal intermediate

member may be placed on top and secured to the upper member and a further upper member is then placed on top of the second intermediate member.

It will be understood that the terms "upper" and "lower" members only apply to said members when the "mat" is used in a horizontal structure such as a road or floor. When used in a wall, column or the like, they will become "outer" and "inner" 75 members.

When used in reinforced round columns, pipes, piles, or the like, the "longitudinal" member is bent to form a circumferential member surrounding the exterior or interior of the structure. When used for walls and beams and rectangular columns the longitudinal members are placed longitudinally of the structure.

In the claims the term "bars" is to be understood as including "rods" and "wires" or other equivalent type of reenforcement.

What I claim and desire to secure by Letters Patent is:—

1. Metal reenforcement for concrete structures, comprising in combination two outer reenforcing frames, and an intermediate reenforcing frame having a zigzag formation and interconnecting the outer reenforcing frames, each frame consisting of a plurality of parallel longitudinal bars spaced apart by a plurality of transverse bars secured thereto, and each frame thereby constituting a separate component unit, the three units being adapted to be assembled together in 100 situ to form a "mat" reenforcement.

2. Metal reenforcement as claimed in claim 1, in which the transverse bars of the intermediate frame are adjacent the angular portions of the latter and contact with the outer frames to space the latter apart.

3. Metal reenforcement for concrete structures, comprising in combination, outer reenforcing frames, an intermediate reenforcing frame having a zigzag formation interconnecting the said outer frames, each frame consisting of a plurality of parallel longitudinal bars spaced apart by a plurality of transverse bars secured thereto, the transverse bars of the intermediate frame contacting with the outer frames to space the latter apart, and a plurality of transverse locking bars fitting in the crests and valleys of the intermediate frame, the frames being adapted to be assembled together in situ to form a "mat" reenforcement.

4. In metal reenforcement for concrete structures, the combination with the elements claimed in claim 3 of transversely arranged zigzag members connected respectively to the upper and lower locking bars to increase the rigidity of the reenforcement.

In testimony whereof I have signed my name to this specification.

JOSEPH HEATON SOUTHERN.
